(57) **CLAIM**

The ornamental design for a carton, as shown and described.

DESCRIPTION

FIG. 1 is a perspective view of the carton showing my new design;

FIG. 2 is a top plan view thereof;

FIG. 3 is a side elevation view thereof, the opposite side and adjacent sides being mirror images;

FIG. 4 is a bottom plan view thereof; and,

FIG. 5 is a plan view of the carton of FIG. 1 in unfolded condition.

The dotted lines shown in the drawing represent fold lines.
